ALPHEUS C. LIPPINCOTT, OF EAST ORANGE, NEW JERSEY, ASSIGNOR TO E. KEELER COMPANY, OF WILLIAMSPORT, PENNSYLVANIA, A CORPORATION OF PENNSYLVANIA.

BOILER-PLUG.

1,285,751.

Specification of Letters Patent. Patented Nov. 26, 1918.

Application filed May 15, 1918. Serial No. 234,623.

To all whom it may concern:

Be it known that I, ALPHEUS C. LIPPINCOTT, a citizen of the United States, residing in the city of East Orange, county of Essex, 5 and State of New Jersey, have invented certain new and useful Improvements in Boiler-Plugs, of which the following is a specification.

The invention relates in general to a sealing device for hermetically closing holes in the apertured walls of pressure confining vessels and the like, and specifically relates to an improvement in boiler plugs of the rolled-in type usually employed in closing 10 the hand hole, the man-hole and similar openings in boiler elements.

In boiler construction it has been known to insert a closed end plug in the hand holes usually with a tapered fit, and by means of 20 a rolling tool the tapered side of the plug is expanded outwardly into a fitting engagement with the outlining edge of the hand hole. When in active operation boilers not only have a high internal pressure, frequently as high as three hundred and fifty 25 pounds per square inch, but this pressure varies from time to time creating the objectionable "breathing" or pulsating action of the several parts. Where this breathing 30 action occurs in boilers equipped with the known types of boiler plugs, it tends to work the hand hole sheets back and forth across their normal planes thus tending to loosen the connection between the edges of the 35 hand holes and the plugs. Further the pressure acting during this time on the closed ends of the plug not only forces the tapered portion of the plug on to the seat provided by the outlining edges of the hand hole but 40 goes farther, and tends to squeeze the plug bodily through the hand hole. Both of these agencies coact eventually in causing 45 a leakage to develop between the plug and its seat, especially after the plug has been in use for a long time.

Accordingly, one of the objects of the invention is to provide a simple form of plug of the type described, in which the rolled-in portion engaging the seat provided by 50 the edge of the hole may be permanently fixed in sealing engagement with the seat, unaffected by the "breathing" action of the hand hole sheet and in which the pressure-receiving, closed, head end will be designed

to defeat any tendency of repeated abnormal 55 high pressure conditions to cause a leakage past the plug.

Broadly, this object is attained by providing a hollow mushroom-shaped plug with a cylindrical neck having a fit in the hole 60 but not necessarily a sealing fit and with an enlarged springy head, the periphery of which is designed to have a sealing engagement with the portion of the sheet surrounding the hole. 65

Another object of the invention for use in situations where it is desirable to remove the plugs described is to provide a simple form of bridging yoke construction for demountably securing the plug in position in 70 such a manner that the yoke will not affect the peripheral sealing action of the pressure acting on the exposed area of the hollow head. 75

Various other objects and advantages of 75 the invention will be in part obvious from an inspection of the accompanying drawings and in part will be more fully set forth in the following particular description of one form of mechanism embodying my invention, 80 and the invention also consists in certain new and novel features of construction and combination of parts hereinafter set forth and claimed.

In the accompanying drawings: 85

Figure 1 is a fragmentary view in section through a boiler element showing a preferred embodiment of my invention in position thereon and with parts broken away to show one form of joint; 90

Fig. 2 is a similar view showing a second form of the invention in axial section; and both figures coact to illustrate a vertical sectional view through the upper portion of a boiler head and showing two ways of utilizing the plug forming the common element in both illustrated forms of closures. 95

In the following description and in the claims parts will be identified by specific names for convenience of expression but 100 they are intended to be as generic in their application to similar parts as the art will permit, for instance the word sheet indicates any form of apertured member and hole or hand hole indicates any form of opening 105 through such member.

In the drawings there is illustrated collectively in the two views a part of a boiler

water leg formed of a tube sheet 10, and hand hole sheet 11 connected by a wrapper sheet 12 and coacting to form a pressure chamber 13 designed to contain a variable 5 high pressure. Water tubes 14 terminate at the tube sheet and opposite each tube the hand hole sheet is provided with a hand hole 15 all as is usual with well known types of such boiler constructions.

10 Referring particularly to the form of the invention illustrated in Fig. 1, there is shown a hollow thin walled metallic mushroom shaped plug 16 for closing the hand hole 15. The plug includes an expansible 15 tubular neck 17 constructed to have a loose, or at most, a driving-tight fit in the hole 15 and preferably projecting slightly beyond opposite ends of the hole. The end of the neck in the chamber 13 is provided with an 20 enlarged hollow head 18 somewhat flattened from the segment of a prolate ellipsoid and having a diameter materially greater than the diameter of the hand hole.

The central ellipsoidal portion of the head 25 forms a pressure receiving sprung wall 19 forming an intensive area of surface exposed to the pressure in the chamber 13. The wall 19 rounds sharply into a ring shaped bearing member 20 facing the portion 21 of the sheet 11 surrounding the hole 15. The bearing member 20 extends almost at right angles to the axis of the tubular neck 17 and on its inner side coacts with the neck to form an internal shouldered peripheral bearing surface 22 adapted to be 35 engaged by an extension of an expanding tool to hold the plug in place against the portion 21 during the process of expanding the neck into sealing engagement with the 40 edge 23 of the hole 15.

Instead of the ring member 20 extending strictly parallel to the portion 21, it is shown slightly inclined from its inner periphery at the neck, outwardly toward its outer periphery which in Fig. 1 is in bearing engagement with the portion 21 of the sheet. It is to be understood, however, that the showing of this incline has been greatly exaggerated in Fig. 1 so as to show clearly 45 the effect of high pressure. In this figure the closure is illustrated in its simplest form but it is intended, especially where high pressure conditions are present in the chamber 13, to insert a ring gasket 24 (shown in 50 Fig. 2) between the member 20 and the portion 21 of the shell, as an additional safeguard.

The gasket is preferably formed of some compressible material, such as lead or copper, and when subjected to high pressure the outer edge of the gasket is compressed more than the inner edge thus forming a circular sealing line concentrically of and spaced from the hand hole.

55 The head may be pressed toward the shell

for any desired distance thus providing for any desired security against leakage.

In the form of the invention illustrated in Fig. 1 the plug is intended to be secured permanently in place by the frictional tight 70 fit between the neck and the edge 23 while the form of the invention illustrated in Fig. 2 is intended primarily for use in those situations where it is desirable to demount the plugs for cleaning the tubes and other interior parts.

In the showing in Fig. 2, a flat substantially disk shaped keeper 25 is positioned within the head and is bridged across the inner end of the neck. The keeper has a 80 diameter slightly greater than the internal diameter of the neck but sufficiently small so that it may be canted angularly to the axis of the neck and inserted into the head through the bore of the neck. The outer 85 edge of that part of the keeper, which is designed to engage the plug is recessed to provide a peripheral shoulder 26 fitting the shouldered bearing surface 22 so as to center the keeper across the opening 15, and to 90 provide a circular bearing for engaging the part of the surface 20 opposite the gasket 24. A spider 27 of conventional form is bridged across the hole 15 and engages the side of the sheet 11 opposite the head 16. A drawing member 28 in the form of a headed bolt is passed through the center of the spider and has its headed end 29 inserted in a bifurcated extension 30 projecting from the front face of the keeper and adjacent its center. 95 A nut 31 is threaded on the outer end of the bolt and bears on the spider to draw the keeper toward the sheet 11 and into position to act through the surface 20 thereby to compress the gasket as previously described 100 in connection with the showing in Fig. 1.

In actual practice it sometimes happens that there is a variation in the diameters of the hand holes, which in some cases would require an excessive expanding of the neck 110 to obtain a fit. In order to expand the necks to take up this difference without affecting the present shape of the head, the angle between the neck and bearing surface is designed in the form of a pronounced reentrant angle or rather curve of small radius as shown at 32 in Fig. 1. The effect of enlarging the diameter of the neck is simply to reduce the diameter of this reentrant angle and make the curve from the end of the 115 neck into the bearing surface more pronounced.

In operation, and referring particularly to the disclosure in Fig. 1, the neck portions of the plugs are inserted in the hand holes 125 through the usual conveniently placed oblong or oval holes and by means of a suitable expanding tool, the necks are expanded into tight engagement with the hole edges 23 when this frictional holding type of con- 130

nection is desired. Especially where a gasket is interposed between the plug head and the sheet, a form of rolling tool is used which can engage the bearing surface 20 to 5 hold the head in gasket-compressing position while the neck is being expanded into position. Without the gasket the plug head is moved forwardly into such an engagement with the sheet that the outer periphery 10 is in light bearing engagement with the portion 21, thus providing two sealing lines, one at the neck and the other near the periphery of the head.

With increase of temperature in the chamber 13, the wall 19 will tend to expand, and increase of pressure in the chamber will tend to flatten the wall both of which actions of the wall will move the outer periphery of the head more firmly into bearing engagement with the sheet, or when a gasket is employed, into position to more firmly compress the gasket.

By this means, with the increased action of those agencies which cause leakage, there 25 will be an increased sealing to defeat any tendency toward leakage. The movement of the periphery of the head will tend to minimize, if not eliminate, any tendency of the neck to creep in the hand hole, thus maintaining a permanency of the sealing joint at 30 this place. In other words, a feature of this connection is to hold the neck in place and to divert pressure actions away from the neck.

35 Increased pressure on the head of the plug acts not to force it through the hand hole but to flatten the periphery of the head into firm binding engagement against the portion of the sheet surrounding the hole. As 40 the diameter of the hand hole reduces during the contraction of the sheet on cooling, the wall 19 of the head simply bellies outwardly into the chamber 13 thus providing for flexibility in the connection between the 45 plug and sheet.

In the form shown in Fig. 2 it is understood that the neck may be rolled in to position as previously described but this is not necessary and a loose or driving fit is 50 sufficient.

The plug with the ring gasket in position about the neck, is inserted in position with the neck extending through the hand hole. The keeper is either carried by the plug 55 head or is inserted into place after the plug is mounted in the hand hole. As the keeper is positioned across the inner end of the neck it tends to resist any tendency of the pressure to collapse the inner end of the neck. 60 Also this keeper acts to hold the inner periphery of the ring gasket, thus assisting to coact with the action of the surface 20 in compressing the outer periphery of the ring as hereinbefore described.

65 The bolt head is inserted in the bifurcated

projection, the spider is inserted over the bolt and the bolt nut is drawn up into tight engagement with the spider.

In this way the pull of the bolt acts centrally on the keeper to draw the same uniformly against practically the entire circumference of the bearing surface 22. 70

Should it be desired to demount the plug temporarily, the spider is demounted and by means of a hook tool engaging in the peripheral recess formed by the member 22 and wall 19, the plug, with the keeper therein, can be displaced into the chamber 13 and afterward re-inserted in place. The spider yoke can then be replaced and the parts are 80 again in operative position.

While one form of the plug has been described as formed with the periphery of the bearing member 20 disposed close to the sheet, it will be understood that even though 85 the plug is not so formed, still the pressure on the head will tend to move the periphery toward and into engagement with the sheet without movement of the neck.

While I have shown and described, and 90 have pointed out in the annexed claims, certain novel features of my invention, it will be understood that various omissions, substitutions and changes in the form and details of the device illustrated and in its operation may be made by those skilled in the 95 art without departing from the spirit of the invention.

Having thus described my invention, I 100 claim:—

1. In a device of the class described, the combination with a sheet subject to a pressure on one side thereof and provided with a hole extending therethrough, of a hollow mushroom shaped plug including a neck 105 fitted in said hole and having a head on the pressure-exposed side of said sheet, the peripheral part of said head being double walled with the walls substantially paralleling the sheet, with the wall adjacent the 110 sheet providing a bearing surface for effecting a seal between the head and the portion of the sheet surrounding the hole, and the other wall being springy, exposed to the pressure present on the pressure-exposed 115 side of the sheet and acting on said bearing surface to move the same toward the sheet.

2. In a device of the class described, the combination with a sheet subject to a pressure on one side thereof and provided with a hole extending therethrough, of a hollow mushroom shaped plug including a neck fitted in said hole and having a head on the pressure-exposed side of the sheet, the side 120 of the head facing the sheet being hollow and extending substantially at right angles to the neck and constituting a bearing surface for effecting a seal between the head and the portion of the sheet surrounding 125 the hole. 130

3. In a device of the class described, the combination with a sheet subject to a pressure on one side thereof and provided with a hole extending therethrough, of a hollow mushroom shaped plug including a neck fitted in said hole and having a head on the pressure-exposed side of the sheet, the side of the head facing the sheet being hollow and extending substantially at right angles 10 to the neck and constituting a bearing surface for effecting a seal between the head and the portion of the sheet surrounding the hole, the outer edge of said bearing surface being movable toward said portion under the action of the pressure acting on the head.

4. In a device of the class described, the combination with a sheet provided with a hole extending therethrough, of a plug for 20 closing said hole, said plug including a head provided with a ring shaped bearing surface facing the portion of the sheet surrounding the hole, and including a neck integral with the head and fitted in said hole for spacing the inner periphery of said ring-shaped bearing surface from the sheet, the outer periphery of said bearing surface being free to move relative to said portion to effect a variable sealing between the head 25 of the plug and the sheet.

5. In a device of the class described, the combination with a sheet provided with a hole extending therethrough, of a plug for closing said hole, said plug including a head 35 provided with a ring shaped bearing surface facing the portion of the sheet surrounding the hole, and including a neck integral with the head and fitted in said hole for spacing the inner periphery of said ring-shaped bearing surface from the sheet, the outer periphery of said bearing surface being free to move relative to said portion to effect a variable sealing between the head 40 of the plug and the sheet and a ring gasket 45 fitted between the bearing surface and said portion.

6. In a device of the class described, the combination with a sheet provided with a hole extending therethrough, of a plug for 50 closing said hole, said plug including a head provided with a ring shaped bearing surface facing the portion of the sheet surrounding the hole, and including a neck integral with the head and fitted in said hole for spacing the inner periphery of said ring-shaped bearing surface from the sheet, the outer periphery of said bearing surface being free to move relative to said portion to affect a variable sealing between the head 55 of the plug and the sheet and said head including pressure receiving means operatively connected with said outer periphery to effect said variable sealing.

7. In a device of the class described, the 60 combination with a sheet provided with a

hole extending therethrough, of a plug for closing said hole, said plug including a head provided with a ring shaped bearing surface facing the portion of the sheet surrounding the hole, and including a neck integral with the head and fitted in said hole for spacing the inner periphery of said ring-shaped bearing surface from the sheet, the outer periphery of said bearing surface being inclined slightly toward the sheet from its inner periphery outwardly toward its outer periphery and a gasket disposed in the space formed by said inclined bearing surface and the adjacent portion of the sheet surrounding the hole. 70 75 80

8. In a device of the class described, the combination with a sheet provided with a hole extending therethrough, of a hollow plug for sealing said hole, said plug provided with a neck fitting in the hole and with a head having a diameter greater than the diameter of the hole, said head including interiorly exposed means providing a tool receiving surface adapted to be engaged by a tool for drawing the head toward the portion of the sheet surrounding the hole in the process of mounting the plug in place. 85 90 95

9. In a device of the class described, the combination with a sheet provided with a hole extending therethrough, a mushroom shaped hollow plug having a neck fitted in and adapted to be rolled into a sealing fit with the edge portion of the sheet outlining the hole, said plug having a hollow head at one end of the neck and extending outwardly 100 therefrom to lap the side portion of the sheet surrounding the hole, said head including an outlining hollow ring facing the sheet and adapted to receive an extended portion of a neck rolling tool whereby said extended portion can act on the head to draw the same toward the sheet during the act of rolling the neck into engagement with the edge of the hole. 105

10. As an article of manufacture, a hollow, mushroom shaped boiler plug including an expandable cylindrical and continuous neck and an enlarged head designed to withstand boiler pressures thereon, said head forming substantially a right-angled external shoulder with the neck, said shoulder constituting a pressure receiving surface. 110 115

11. As an article of manufacture, a hollow, mushroom shaped boiler plug including a continuous tubular neck and an enlarged head, said head forming substantially a right-angled external shoulder with the neck, and a ring gasket fitted to said neck and engaging to said external shoulder and designed to be compressed by pressure on 120 125 said head.

12. In a device of the class described, the combination with a sheet provided with a hole extending therethrough, of a closure including a plug for closing said hole and 130

- having a head with an internal diameter greater than the diameter of the hole, a keeper for engaging the interior portion of the head facing the portion of the sheet surrounding the hole and adapted to act thereon to draw the head toward said hole-surrounding-sheet-portion.
13. In a device of the class described, the combination with a sheet provided with a hole extending therethrough, of a closure including a plug for closing said hole and having a head with an internal diameter greater than the diameter of the hole, a keeper for engaging the interior portion of the head facing the portion of the sheet surrounding the hole, said keeper provided with means for centering the same in the head and also provided with means for drawing the head toward the sheet.
14. In a device of the class described, the combination with a sheet provided with a hole extending therethrough, of a plug for closing said hole, said plug including a tubular member fitting in said hole and a member extending outwardly from the tubular member and forming an internal shoulder therewith, a keeper provided with a peripheral shoulder fitting said internal shoulder and means acting on said keeper for holding the portion of the plug surrounding the hole in position.
15. In a device of the class described, the combination with a sheet provided with a hole extending therethrough, of a plug for closing said hole, said plug including a tubular member fitting in said hole and a member
- extending outwardly from the tubular member, a drawing member extending centrally through said tubular member and a connecting member extending from said drawing member to said outwardly extending member whereby the pull of said drawing member is transmitted directly to the portion of said plug surrounding the hole to hold the same relative to said sheet.
16. In a device of the class described, the combination with a sheet provided with a hole extending therethrough, of a hollow mushroom shaped plug having its head positioned on one side of the sheet and its neck fitted in said hole, a spider bridged across the hole on the opposite side of the sheet, a keeper positioned within the head and engaging the side thereof disposed opposite the sheet and bolt connecting the keeper and spider and a gasket disposed between the head of the plug and the adjacent side of the sheet, said gasket designed to be compressed by the tightening up of said bolt.
17. In a device of the class described, the combination of a sheet provided with a hand hole, a mushroom shaped plug having a neck fitted in said hole and immovable relative thereto, the periphery of the head of said plug being resilient and adapted to be acted upon by the pressure on said head to force the same toward said sheet.
- Signed at New York, in the county of New York and State of New York, this 8th day of May, A. D. 1918.

ALPHEUS C. LIPPINCOTT.
